UNITED STATES PATENT OFFICE.

WILLIAM O. RENKIN, OF ORADELL, NEW JERSEY, ASSIGNOR TO QUIGLEY FURNACE SPECIALTIES CO., INC., A CORPORATION OF NEW YORK.

SEMI-AUTOMATIC COMPRESSED-AIR TRANSPORT SYSTEM.

1,301,167.

Specification of Letters Patent. Patented Apr. 22, 1919.

Application filed July 29, 1918. Serial No. 247,267.

To all whom it may concern:

Be it known that I, WILLIAM O. RENKIN, a citizen of the United States of America, residing at Oradell, county of Bergen, State 5 of New Jersey, have invented certain new and useful Improvements in Semi-Automatic Compressed-Air Transport Systems, of which the following is a specification.

My invention relates to systems for the 10 transportation of powdered coal or other finely divided material from a supply center to various different local storage bins or other receptacles, and comprises an apparatus by which one person located at the 15 supply center can operate the entire system from that point through the assistance of devices which are semi-automatic in action. The apparatus could also be used for handling liquids, but finds its most useful application to systems for powdered coal transportation from a main storage tank to a 20 variety of separate consumption points, such as, for instance, is described in U. S. Patent No. 1,177,045, to Magarvey *et al*, granted 25 March 28, 1916.

Under existing commercial conditions the 30 respective furnaces are apt to be run by operatives who cannot be relied on to watch their respective coal supplies and telephone in to the main station when, and how much, 35 additional fuel supply is needed. Moreover it is better and more economical to have the skilled operative who manipulates the transportation plant as a whole, attend to the refilling of the different local bins at regular 40 intervals so as to leave him free for other work at other times, rather than to hold him continually subject to the haphazard calls of the different furnace operatives for intermittent delivery of fuel to them. To this 45 end I have invented the particular combinations of apparatus hereinafter described which are semi-automatic in their operation,—that is to say the devices at each local 50 bin can be set so as to connect that bin with the main supply conduit, and then the branch to that bin can be cut out by the central operator when his scales tell him that he has sent to that bin the amount of coal which his previous investigation has shown was needed there.

The best form of apparatus embodying

my invention at present known to me is illustrated in the accompanying four sheets of drawing, in which:

Fig. 1 is a side elevation of the main blowing tank and one local bin connected thereto, together with the controllers supplied thereby to feed a given furnace, parts being broken away and others shown diagrammatically.

Fig. 1^a is a similar view of two other local bins, constituting, with the apparatus shown in Fig. 1, a complete system.

Fig. 2 is an enlarged detail side elevation 65 of one of the compressed air valves for controlling the coal supply switch valves at certain stations, and the operating connections therefor, parts being broken away.

Fig. 3 is an edge view of the valve shown 70 in Fig. 2, and its connections.

Fig. 4 is an enlarged detail rear elevation 75 of one of the coal supply switch valves and its operating motor.

Fig. 5 is a plan view and horizontal sec- 75 tion on the line 5—5 of Fig. 4, and

Fig. 6 is a detail sectional view showing the air valve passages.

Throughout the drawings like reference 80 figures indicate like parts.

In the general system to which my invention is usually applied, there is a blowing tank 1, mounted on a balanced scale 2, and provided with flexible connections to all fixed portions of the system so that the operator can tell by the scale readings from time to time the amount of pulverized material which he has discharged from this blowing tank or supply tank. The manipulation by which such graduated quantities of 85 material are discharged is exercised through the control lever 3, and the compressed air valve 4, in the manner set forth in the pending application of Harry Arthur Kimber, Serial No. 214,755, filed January 31, 1918. 90 The pulverized coal discharged from the supply tank 1, passes out through the main line conduit 5, to various branch storage bins 10, 110, 210, &c., from which it is supplied through controllers 6, 6, operated by 100 motors 7, 7, and belt and pulley connections 8, 8, to the furnace or furnaces at the respective locations indicated. The controllers 6, 6, are preferably of the construction shown

and described in my pending application Serial No. 204,788, filed November 30, 1917.

In systems of the general construction above described, as heretofore operated, each operator at a branch or local station has been required to keep track of his local fuel supply and when the same approached exhaustion telephone in to the supply station operator stating the amount of additional fuel required. The supply station operator when ready to deliver the amount required at that particular station would telephone back to the local operator to set his switch valve 11, or 111, as the case might be, in the position which would close the main line conduit at that point and open the branch connection 12 or 112 to the local storage bin. The supply station operator would thereafter send the required amount of fuel through the main line of the system to the local bin in question and, when the supply had been delivered, telephone the local operator to close his switch valve and reopen the main line connection.

My present invention overcomes the delay and general awkwardness of the procedure above described by making the action of the switch valves semi-automatic and controllable by the supply operator at the supply station through some such combinations of elements as are herein described.

On the axis of each switch valve, as 11, is mounted a lever 13, which at one end carries contact points 14, coöperating with stationary points 15, the whole constituting a circuit controller for an electric circuit extending from the local station to the supply station. The other end of the lever 13, is connected to some motor device, as by means of the disk-shaped end 16, which extends into a slot in the trunk piston 17, of a pneumatic motor composed of the opposed stationary cylinders 18, 18. The trunk piston makes an air-tight joint connection with said cylinders by means of the outside stuffing boxes 19, 19. This pneumatic motor or switch valve reversing device is operated by a controller comprising an air valve 20, having the curved passageways 20^a and 20^b shown in Fig. 6 of the drawings, which control the admission and exhaustion of compressed air or other motive fluid, to and from cylinders 18, 18. The fluid enters from compressed air pipe 9, through branches 21, 121, &c., air valve 20, or 120, and air pipes 23 or 24, or 123 or 124, to either cylinder 18, and thereafter passes back through said pipes and valves to an exhaust, as 21^a.

In the case of storage bin 110, the same apparatus is a duplicate of that for storage bin 10, having the controller valve 120, pipes 123, 124, air motor or reversing device composed of cylinders 118, 118, trunk piston 117, switch valve 111, lever 113, and electric contact points 114, 115.

On the spindle 25 or 125, of each controlling valve 20, or 120, as indicated in the enlarged detail views, Figs. 2 and 3, there is mounted a cut-away pulley, 26, or 126, to which a retracting spring, 27, or 127, is attached, the other end of said spring being connected to any convenient fixed point. A pull cord or chain, 28, or 128, runs over the other side of each pulley and is connected at one end to said pulley, as indicated at 28^a, while the other end is allowed to hang pendant to point within easy reach of the local operator standing on the floor of the branch station. Also, on the spindle 25 or 125, of each valve there is fastened a brake drum, as shown at 29, around which extends a brake band 30, one end of which is connected to fixed point or anchorage, as 31, while the other end is connected to the core of a solenoid, 32 or 132, supported in a stationary position by any convenient structure. One end of the winding of the solenoid 32, is connected by one wire of circuit 33, through circuit breaker 14—15, telltale lamp 34, and manually operated circuit controller or switch 35, to one pole of any source of electric current supply conventionally represented by the battery 36, while the other end is connected to the other pole of said source of current by another portion 95 of said circuit 33.

In the same way each other motor controlling valve is operated by a pull cord, a tension spring, a solenoid, and an electric circuit, as 133, extending through the circuit breaker on its local switch valve to the supply station through a telltale lamp, as 134, and manually operated circuit controller, as 135, there located, to a source of current supply 36.

On each bin is a coal gage composed of a weight, as 41, suspended in the interior of the bin by any convenient means such as chain or cord 38, extending up over a guide sheave, as 40, and then downward alongside a gage board such as 37, and carrying a pointer, such as 39, coöperating with said gage board. The corresponding parts for bin 110, are shown at 137, 138, 139, and 140, and for bin 210, at 237, 238, 239, 240 and 241.

The operation of the above described apparatus is as follows: The operator of the supply station makes periodic trips around a circuit including all the branch storage and consuming stations and at each station he pulls down upon the pull cord 38, 138, or 238, until the weight 41, 141, or 241, is freed from the mass of pulverized coal contained in the storage bin at that station. Upon releasing the pull cord, the weight 125 will then fall back upon the surface of the body of coal and the pointer 39, 139, or 239, will indicate on the gage the amount of coal in that bin. Knowing the capacity of the bin, the operator can then tell the amount of 130

coal required to fill that bin and make note of the same. He next pulls down upon the cord or chain 28 or 128, which rotates the cut-away pulley 26 or 126, against the open position of the spring 27 or 127, and turns the valve 20 or 120 in such position that the compressed air branch 21, is connected through the passage 20^a to pipe 24, which admits compressed air to the lower cylinder 18, forces up the trunk piston and causes the local switch valve to close off the main line conduit 5, at that point and open the branch conduit, as 12, connecting the main line conduit with the local bin. This is the position of the controlling device shown in Figs. 2 and 3. The same operation causes the upper cylinder 18, to be connected through pipe 23, and valve passage 20^b, with the exhaust opening 21^a. It also closes the circuit breaker 14—15 and completes the circuit 33, from source of current 36, through solenoid 32, lamp 34, and manually operated circuit breaker 35, at the supply station (it being understood that the operator before starting out on his tour has closed all of the manually operated circuit breakers 35, 135, &c., at the supply station). The energizing of the solenoid, as 32, of course causes it to put the brake band, as 30, under tension and it, in coöperation with the brake drum, as 29, holds the controlling valve 20, in the position last described and shown in Figs. 2 and 3, against the pull of the spring, as 28, so long as the circuit 33, remains closed. The glowing of lamp 34, shows any observer at the supply station that the switch valve 11, is in position to connect branch conduit 12. The sending station operator having completed the circuit, set all the switch valves 11, 111, etc., in the position to connect their respective bins, and returned to the supply station, proceeds to fill the various local storage bins as follows: He first sends out through the main line conduit 5, the amount of coal required for the first storage bin 10, by manipulating the control lever 3, and air valve 4, on the supply tank 1. When the scale 2 shows that the necessary amount for the first storage bin has been sent out, the operator pulls the corresponding manually operated circuit breaker 35, which opens circuit 33 and deenergizes solenoid 32, releasing brake band 30, and permitting the spring 27, to reverse the control valve 20. Lamp 34 then goes out, showing that this branch circuit is deenergized. This sends the compressed air from branch 21, through pipe 23, into the upper cylinder 18, and connects the lower cylinder 18, through pipe 24, with the exhaust opening 21^a. This operates the pneumatic motor to perform a double function of shifting the switch valve 11, so as to open the main line conduit to the next station and close the branch conduit 12, and also to break the circuit 33, at another point

by separating contact points 14 and 15, the parts taking the positions shown in Figs. 1, 4 and 6.

Thereafter the coal from supply tank 1, passes farther along through main line conduit 5, until it comes to the open switch valve 111, of the second storage bin 110, and passes down into said bin. After the amount which the supply station operator's record shows is required for the second storage bin 110, has also been sent out, as indicated by the scale 2, said operator cuts out storage bin 110, by pulling the circuit breaker 135, and the material then passes on to the next storage bin, and so on. Figs. 1 and 1^a, taken together show the system in the position assumed after bin 10, has been filled, and while bin 110, is being filled. The position of pointer 139, shows that bin 110, only needs a small amount of coal, having been found nearly full when the operator tested it. The position of pointer 39, shows that bin 10, was nearly empty when the operator tested it, and the same is true of bin 210.

The storage bin 210, at the end of the main line conduit 5, has no switch valve and is provided only with the gaging device consisting of the gage board 237, the pull cord 238, running over pulley 240 to the interior weight 241, and carrying the pointer 239, coöperating with the gage board 237. When the central station operator's record shows that the amount of coal necessary to fill all the storage bins, including the end one 210, has been sent out he simply shuts down his sending apparatus and goes about his other duties. If, through any oversight, he continues to send out pulverized coal, after the last bin has been filled, it will simply blow off through the relief opening 242, and distribute itself around the surrounding neighborhood until the exasperated inhabitants have telephoned in the to supply station to have the oversight rectified. In the same way, the other storage bins are provided with relief outlets 42, 142, &c., through which surplus material will be discharged if the switch valve serving any bin is not closed after the bin has been filled. In this way any clogging up of the conduits and connected valves, such as would otherwise put the system out of operation, is avoided.

By the use of my invention the control and operation of the whole compressed air transportation system is concentrated in the hands of one man who soon becomes highly skilled therein, while the manipulation of the powdered coal controllers can be taken care of by the furnace men.

Having described my invention, I claim:

1. In a fluid pressure transportation system comprising a main supply station, a plurality of branch storage stations, a main line conduit leading from the supply station, a branch conduit leading from said main

- line conduit to each branch storage station, means for forcing predetermined portions of the material at the supply station through the conduits to the branch stations, and 5 switch valves at certain branch points controlling the branch and main line conduits at said points, the combination with said switch valves of a motor for automatically operating each of the valves, a resilient controlling device for each motor normally tending to assume the position which will cause the motor to operate its particular switch valve so as to close the branch conduit and open the main line conduit at that point, 10 means for restraining said controlling device in the opposite position of adjustment whereby the valve is operated to open the branch conduit and close the main line conduit at that point, and means operable from the supply station, by which any one or 15 more of said controlling devices may be released from its restraining means.
2. An apparatus such as set forth in claim 1 combined with manually operated means 25 for setting each control device in the position which will cause the motor controlled by it to turn the corresponding switch valve into the position which opens the branch conduit.
3. In a fluid pressure transportation system comprising a main supply station, a plurality of branch storage stations, a main line conduit leading from the supply station, branch conduits leading from said main line 30 conduit to each branch storage station, means for forcing predetermined portions of the material at the supply station through the conduits to the branch stations, and switch valves at certain branch points controlling the branch and main line conduits at said points, the combination with said switch valves of pneumatic motors operatively connected one to each of the switch valves, an air controlling valve for each 35 motor, a spring normally holding each air controlling valve in the position which operates the motor to turn the switch valve so as to close the branch conduit and open the line conduit, means for turning said controlling valve against the flexure of the spring into the position which will operate the motor in the opposite direction, means brought into action when the switch valve is open to hold each air control valve in its 40 last mentioned position against the pressure of its spring, and means operable from the supply station for independently disabling each of said holding means.
4. In a fluid pressure transportation system 45 comprising a main supply station, a plurality of branch storage stations, a main line conduit leading from the supply station, a branch conduit leading from said main line conduit to each branch storage station, means for forcing predetermined portions of the 50 material at the supply station through the conduits to the branch stations, and switch valves at certain branch points controlling the branch and main line conduits at said points, the combination with said switch valves of pneumatic motors operatively connected one to each of the switch valves, an air controlling valve for each motor, a spring normally holding each air controlling valve in the position which operates the motor to turn the switch valve so as to close the branch conduit and open the line conduit, a pull cord for turning each of said air control valves into its opposite position against the flexure of its spring, a brake drum on each 55 valve, a coöperating brake and a solenoid for actuating the same, a source of electric current and a circuit therefrom through each solenoid, a controller in each circuit operated by the corresponding switch valve to close the circuit when the switch valve has opened the branch conduit and to open it when the switch valve has closed said branch conduit and opened the line conduit at that point, and a separate, manually operated controller for each said circuit, all of which controllers last mentioned are located at the supply station.
5. An apparatus such as set forth in claim 1 combined with means located at the supply station for indicating the amount of material sent out through the line conduit during any given period of time.
6. An apparatus such as set forth in claim 1, combined with a telltale device for each switch valve adapted to show its position, which telltale devices are all located at the supply station.
7. An apparatus such as set forth in claim 4 combined with an electric lamp in each circuit, all of said lamps being located at the supply station near the manually operated circuit controllers.
8. The combination with a main line conduit, a series of branch conduits connected thereto, means for transporting pulverized material therethrough on a current of compressed air, a pipe for compressed air supply to said conduit extending along the same, and switch valves located at each branch point each controlling passage through the main line conduit and the branch at that point, of mechanism actuated by air from the compressed air pipe to operate the switch valves and controlling devices for said mechanism located one near each branch point, but all provided with connections through which they are operable from one point and individually operable from the respective branch points.
9. In a system for transportation of flowing materials by compressed air the combination with a supply station, a plurality of storage stations each provided with blow-off openings to the atmosphere, a main line conduit leading from the supply station, a branch conduit leading from said main line conduit to each storage station, means for forcing predetermined portions of the material at the supply station through the conduits to the storage stations, and switch valves at certain storage points controlling the branch and main line conduits at said points, the combination with said switch valves of pneumatic motors operatively connected one to each of the switch valves, an air controlling valve for each motor, a spring normally holding each air controlling valve in the position which operates the motor to turn the switch valve so as to close the branch conduit and open the line conduit, a pull cord for turning each of said air control valves into its opposite position against the flexure of its spring, a brake drum on each valve, a coöperating brake and a solenoid for actuating the same, a source of electric current and a circuit therefrom through each solenoid, a controller in each circuit operated by the corresponding switch valve to close the circuit when the switch valve has closed said branch conduit and opened the line conduit at that point, and a separate, manually operated controller for each said circuit, all of which controllers last mentioned are located at the supply station.

conduit extending from the supply station to the farthest storage station, branch conduits from the main line conduit to the other and intermediate storage stations, a 5 switch valve controlling the junction of each branch conduit and the main line conduit, and means for forcing measured quantities of material from the supply station out through the conduits, of means controllable 10 from the supply station actuating all said switch valves.

10. In a fluid pressure transportation system comprising a main supply station, a plurality of branch storage stations, a main line 15 conduit leading from the supply station, a branch conduit leading from said main line conduit to each branch storage station, means for forcing predetermined portions of the material at the supply station through 20 the conduits to the branch stations, and

switch valves at certain branch points controlling the branch and main line conduits at said points, the combination with each of said switch valves of mechanism normally tending to turn it into position to shut off 25 the branch conduit and open the main line conduit, manually operated means for counteracting the normal tendency of the said mechanism and causing the valve to turn in the opposite direction, whereby the branch 30 conduit is opened and the main line closed, electrically operated means for locking the valve in the last described position, a circuit for operating said electrical means extending to the supply station, a circuit controller for said circuit located at the supply station, and a second circuit controller in 35 said circuit located near the valve.

WILLIAM O. RENKIN.
